GARMENT HANGER TRACK OFFSET

Carl Dahlberg, Duluth, Minn., assignor of one-half to Martin I. Friedman, Duluth, Minn.

Application November 13, 1947, Serial No. 785,619

2 Claims. (Cl. 211—123)

1

This invention relates to the art of dry cleaning and has special reference to a device for simplifying the examining of garments in such an establishment.

It is well known that most dry cleaning establishments are equipped with an elevated continuous track, usually common pipe, along which garments are moved while on common garment hangers. Almost every establishment has the cleaned garments examined before they are delivered to make sure they are properly cleaned. On an ordinary garment track this examining requires the lifting of the garment and hanger off of the track, turning it around, and re-hanging same in order to properly inspect the garment. Then, the garment and hanger must again be lifted off the track and put back in original position. This latter movement being necessitated from the construction of the track in that the same is suspended by hooks or brackets which must all project or extend to the same side in order to provide one free side on which the garment hangers may be slid along without being lifted over each suspending bracket.

It is obvious that the examining of garments in ordinary dry cleaning establishments involves much wasted time and effort. To overcome this disadvantage is the principal object of the instant invention.

Another object is to provide a device which, while eliminating wasted time and effort, can also be easily incorporated in the common garment track so that the least modification of the common procedure and equipment is required.

Another object is to provide such a device that will be a part of the track and not interrupt same with joints or the like which might cause annoyance if not difficulty in moving garments on hangers therealong.

Another object is to provide a device to facilitate the selection of garments while on hangers, for example in a store.

Other objects and advantages will appear as the description of the invention proceeds.

In the accompanying drawing forming a part of this application:

Fig. 1 is a top plan view of a track offset embodying the invention.

Fig. 2 is an enlarged perspective view of one of the track offsets partially installed within a garment rack track.

In the drawing the reference numeral 1 represents a portion of a common elevated garment rack track such as are used in dry cleaning establishments along which garments on garment

2

hangers 2 are moved from place to place by sliding same thereon.

As pointed out heretofore, the track is suspended by means of suitable brackets, not shown, 5 all of which extend from the same side thereof in order to provide a free side to permit the hangers to be slid along without interruption by the brackets, making it necessary to have all hangers facing the same way, that is, with the free end of the hook in the direction of the brackets.

To permit the examining of garments without removing same from the track I have provided the track offset 3 which is clearly illustrated in the drawings. The reference numerals 4—4 indicate connector portions by means of which the offset may be readily installed within a common pipe track.

The instant showing of the connector is that of providing a screw-threaded connection to the 20 track, however, it is deemed apparent that other suitable means may be provided if desired. The connectors are preferably of the same outside diameter or size and shape as the track, thereby providing an uninterrupted joint as clearly seen in Fig. 2 over which the hangers will slide easily.

The examining point or track offset 3 is preferably made of a single piece of strap metal and may be secured to the connectors in any desired manner, however, it has been found very satisfactory to install the straight ends 5—5 of the offset 3 within a bifurcation of the connector and install a pin 6 transversely through the connector and the ends 5 to hold same together, thus providing means whereby the connectors may be permanently installed in the track and the offset portion may be removed by pulling the pins 6 if desired.

Intermediate of the connectors the offset member 4 is bent to preferably a substantially semi-circular bight with somewhat arcuate corners joining said bight with the straight end portions 5—5 to provide a more smooth and easier track on which the hangers 2—2 may slide.

It is to be noted that the upper edge of the offset 3 is in the same plane as the upper edge of the track 1 so as to provide a smooth continuous track, free of obstructions. The offset portion occurs laterally of the track as shown to function properly as desired.

In operation the device is employed as follows: Garments on hangers 2 are moved along the track toward the offset 3 or examining position. The inspector then slides each garment and hanger individually on to the offset as indicated in dotted lines at 7 where one side of the gar-

ment may be readily examined. Upon completing the examination of that side of the garment, the hanger is slid around to the other side of the bight as indicated at 8 where, obviously, the other side of the garment automatically comes into view and may be readily examined. If the garment passes the inspection, it is merely slid along the offset on to the next section of track, not shown, where it is disposed of as desired. Garments which do not pass the inspection are, of course, sent back to have further cleaning operations performed thereon.

It is to be noted that the inspection of the garments may be accomplished without the inspector's having to move from his position or lift the garments around at all, the only action required of the inspector is to slide the garment hangers along on the track, the inspector being able to make his examination very much more quickly since he does not lift and turn even once to accomplish the inspection. The resulting saving of both time and labor will be readily appreciated by those engaged in the art.

It is deemed apparent that while the instant offset has been shown and described as being made of strap metal, the same may be made of a piece of pipe or other suitable material if desired. The instant showing has been preferred due to the difficulty involved in bending a piece of pipe to such a sharp bight.

It is to be noted that while I have shown a semicircular bight portion 3, same may be angular, substantially triangular, or otherwise and still function equally as well, the requisite form being such that as hangers are slid therealong, they are first moved toward the inspector presenting one side to view and then the hanger is automatically turned and moves away from the inspector presenting the other side to view.

Having thus described my invention, what I claim is:

1. In a track along which garments are slid on hangers, said track being substantially straight along a portion thereof and in a horizontal plane, a bight formed in and interrupting said straight track, said bight being relatively small and extending substantially horizontally from said track whereby both sides of a garment are presented to view from a position adjacent said bight as said garment is moved over said bight, said bight comprising a thin strip of metal having substantially aligned ends with said bight intermediate same, and a connector on each of said ends for securing said bight to adjacent portions of said track.

2. The structure as set forth in claim 1 and said connector portions being bifurcated to receive said ends to support said bight.
